UNITED STATES PATENT OFFICE.

PERCY E. VARNEY, OF HADDON HEIGHTS, NEW JERSEY.

CLUTCH.

SPECIFICATION forming part of Letters Patent No. 742,816, dated October 27, 1903.
Application filed March 2, 1903. Serial No. 145,710. (No model.)

To all whom it may concern:

Be it known that I, PERCY E. VARNEY, a citizen of the United States, and a resident of Haddon Heights, New Jersey, have invented 5 certain Improvements in Clutches, of which the following is a specification.

The object of this invention is to provide an improved device by which a driving and a driven member may be operatively connected 10 at will, it being especially desired that such device while being certain in its action and simple in construction shall at the same time require but a minimum of power for its application or release. This object I attain as hereinafter set forth, reference being had to the 15 accompanying drawings, in which—

Figure 1 is a side elevation of my improved clutch, the cover of the inclosing casing having been removed and the supporting-shaft 20 being shown in section. Fig. 2 is a vertical sectional view of the clutch, taken on the line 22, Fig. 1. Fig. 3 is a side elevation of one of the arms fixed to and projecting from the shaft upon which the device is supported, the 25 view showing the gripping-shoes and the method of their support. Fig. 4 is a side elevation, partly in section, showing a special form of my improved clutch. Fig. 5 is a side elevation of a portion of the clutch shown in 30 Fig. 4, illustrating the detail construction of the same; and Fig. 6 is an elevation, partly in section, showing a special form of mechanism for throwing the clutch into and out of action.

35 In the above drawings, A represents a shaft which in the forms of the device shown in Figs. 1, 2, and 6 is hollow, though, as herein-after set forth, the mechanism of the device may be slightly modified, so that it may be 40 solid. In the present instance the shaft constitutes one member of the clutch, and a pulley B, made with a removable cover b, so as to be freely rotatable upon and independent of said shaft, forms the second member of 45 said clutch.

Keyed or otherwise fixed to the shaft A is a collar a, having any desired number of radially-projecting arms a'—in the present instance two—on each of which is carried a slide 50 a², so constructed as to be free to move there-upon toward or from the shaft A, each slide in turn having pivotally fixed to it a swing-

ing shoe-carrying arm a⁴ by means of a pin a³ through a portion of the slide a² distant from said shaft A. From Figs. 2 and 3 it 55 will be seen that this arm a⁴ is U-shaped and may be described as carrying on the inside of each of its arms a gripping-shoe a⁵, these shoes being held in position, so as to move independently of their supporting-arm a⁴, by means of pivots a⁶. The adjacent faces of each of these shoes are formed on circular arcs concentric with the shaft A and may be made of such dimensions as are required by the power to be transmitted. The interior 65 of the pulley B, which in the present instance forms a casing, is provided with an inwardly-projecting flange or rib b', also concentric with the shaft A and having its inner and outer faces formed to coact with the gripping- 70 shoes a⁵.

The collar a is slotted circumferentially at points adjacent to each of the shoe-carrying arms a', which are provided with extended portions a⁷, entering said slots and to some 75 extent coacting with the sides of the same to relieve the strain on the pivot a³ when the shoes grip the flange b'. In the forms of my device shown in Figs. 1 to 3, inclusive, these extensions a⁷ are of a beveled or triangular 80 form, and there is an opening through the collar a through the wall of the shaft A and opening into its interior through which operates a bar or bolt a⁸, formed with a U-shaped recess in its outer face for the reception of 85 the extension a⁷ of the arm a⁴. This piece a⁸ is movable radially through the above-mentioned openings in the shaft A and the collar a, being formed to be pushed by means of a beveled section c upon an operating-piece C, 90 rigidly fixed to an operating-rod c' and carried in the hollow of the shaft A. The piece C has cylindrical sections c² and c³ of different diameters united by the beveled surface c, and the piece or pieces a⁸ abut upon these 95 parts without revolution, or they may be so arranged as to turn independently of the shaft A.

Each slide a² is preferably provided with a lug a⁹, through which extends a headed bolt 100 D, threaded into the collar a and provided with a jam-nut d, whereby it may be retained in any desired position.

In operation as long as it is desired that

the member A shall turn independently of the member B the operating-rod c' is held in such position that the cylindrical portion c^3 of the block or piece C keeps the radially-movable piece a^8 in its extreme outward position. By reference to Fig. 3 it will be seen that when so held the V-shaped recess in the end of said section engages the triangular projection a^7 on the swinging arm a^4 and by virtue of the arrangement of said parts holds its piece so that the pivots a^6 of the shoes a^5 are in a radial line joining the center line of the shaft A with the pivot a^8 . It will be understood that since the shaft A is rotating the collar a the arm a' with all the parts carried thereby are also rotating and that the tendency of the slide a^2 is to move away from the center of the shaft under the action of centrifugal force. Since the swinging arm a^4 is held to said slide by its pivot a^3 , so that its center of gravity is between said pivot and the shaft A, it will be seen that except when said center of gravity is in the radial line joining this pivot and the center of said shaft a^4 , with its shoes, tends also under the action of centrifugal force to turn on the pivot a^3 in an endeavor to move away from the shaft A. It will be understood, further, that this action is resisted by the rod or bolt a^8 , so that when it is desired to operatively connect the two members of the clutch all that is necessary for this purpose is to move the rod c' so that the portion c^2 is in line with said bolt. Under this condition the projection a^7 , which, it will be understood, is pressing upon either side of the recess in the bolt a^8 , will force said section inwardly, thereby permitting the swinging arm a^4 to turn to a limited extent upon its pivot a^3 . The utility of the relative placing of the flange b' and of the pivot a^3 for the arm a' will be appreciated from the above description of the action of said arm, for on account of such arrangement practically all of the mass comprised by the arm and its attached parts remains in unstable equilibrium and out of engagement with said flange b' as long as the piece a^8 is in action. As soon, however, as the restraining effect of said piece is removed the mass turns to a greater or less extent on the pivot a^3 and, owing to the long lever-arm, due to the distance of the point of engagement of the shoes from the pivot and to the relatively great force exerted on said lever-arm due to the arrangement above noted said shoes grip and hold the two members of the clutch together much more certainly and strongly than has hitherto been possible. Such action immediately moves the center of support of the inner shoe a^5 farther from the center of the shaft A, with the result that the curved surface of this shoe comes in contact with the inner surface of the flange or rib b' and being curved on the same radius as this latter is immediately turned on its pivot a^6 , so that said curve is still concentric with the center of the shaft. Such turning of this inner shoe a^5 causes it to approach the outer shoe, which has been similarly turned on its pivot, though to a less extent, with the result that both shoes grip their respective coacting surface of the rib b' and pull the slide a^2 inwardly on the arm a' . By this means the two members of the clutch will be operatively coupled and will remain so until by the suitable movement of the rod c' the beveled portion of the rod C is brought against the inner end of the bolt a^8 , so as to force it outwardly and cause the sides of its recess to engage one side of the projection a^7 . As said bolt a^8 is forced outwardly to its full extent the swinging arm a^4 is forced to turn on its pivot a^3 until the lines of the pivots a^6 of the gripping-shoes are again in a radial line from the center of the shaft A, which movement of said arm causes the shoes to release their grip upon the flange b' , and thereby release the two members of the clutch. This action, in addition, permits outward motion of the slide a^2 with its parts as a whole upon the arm a' , and its motion is limited by the head of the bolt D striking the lug a^9 , said bolt being given a permanent adjustment when the parts of the clutch are originally assembled.

If desired, the swinging of the shoe-carrying arm a^4 and the consequent connecting or disconnecting of the members of the clutch may be accomplished by means other than the longitudinally-movable rod c' and block C within the hollow shaft, for, as shown in Figs. 4 and 5, I may, if desired, provide a longitudinally-movable collar E, loosely carried on the shaft A' and having a portion projecting into the interior of the casing formed by the member B. This collar has a projecting lug e within said casing, in which is formed a recess or notch for the reception of a pin or projection a^{10} from the inner end of the swinging arm a^4 . The outer face of the collar E is provided with a triangular projecting portion e' , and there is a second collar F, carried by the shaft and provided with a V-shaped recess for the reception of said projection, this latter collar, however, being splined to the shaft A', so as to be free to move longitudinally and being provided with an angular groove for the reception of any desired device whereby it may be operated. There is a certain amount of lost motion between the projection a^{10} from the swinging arm a^4 and the recess in the lug e, and the various parts of the device are so arranged that as long as the gripping-shoes engage the flange b' the collar E will have the end of its projection e' displaced to one side or the other of the end or apex of the triangular recess of the collar F. In order, therefore, to disengage the two members of the clutch from each other, the said latter collar is moved longitudinally on the shaft and the sides of this recess made to engage the sides of the projection e' , thereby turning the collar E relatively to the shaft to an extent sufficient to move the swinging arm

a^4 with the gripping-shoes, so that the pivots of said shoes are, as before, on a radial line from the center line of the shaft A.

A further modification of the operating mechanism is shown in Fig. 6, where, as in Figs. 1 and 2, a hollow shaft A is used with a longitudinally-movable block and an operating-rod c' to force outwardly a piece G. This latter is attached to one end of a lever g , pivotally supported at g' on a lug from the collar a , and, as in the former instance, motion of this lever is made to forcibly turn the swinging arm a^4 on its pivot a^3 , so as to move the shoes a^5 out of engagement with the flange b' , or, on the other hand, to permit said shoes to grip said flange when the rod c' is properly moved, so as to allow the piece G to be moved inwardly under the action of the centrifugal force acting on the arm a^4 and its shoes. If desired, a lug a^{11} may be provided on the supporting-arm a' , so as to prevent movement of the lever g to the wrong side of the radial line after the piece G has been moved, so as to cause the shoes to disengage the flange, it being understood that such provision makes it necessary that the arm a^4 should move in the direction of the arrow in Fig. 6 in order to permit the shoes to grip.

I claim as my invention—

1. The combination in a clutch, of a driving and a driven member, an arm pivotally supported upon one member, means carried by said arm for gripping a suitable portion of the other member, the point of support of said arm being so placed that it is farther from the center of revolution of the clutch than is the portion of the other member to be gripped, with means for holding said arm in a position such that one member of the clutch may turn independently of the other, substantially as described.

2. In a clutch, the combination of a driving and a driven member, a piece operatively connected to one of said members and supported so as to be free to move bodily toward and from the center of revolution of the clutch, an arm pivoted to said piece having means for gripping a suitable portion of the second member of the clutch, and means whereby said arm may be retained in a position such that the two members of the clutch are free to turn independently of each other, substantially as described.

3. The combination in a clutch, of a driving and a driven member, an arm fixed to one member, a piece supported thereby so as to be free to move bodily toward and from the center of revolution of the clutch, an arm pivoted to said movable piece, shoes carried by said pivoted arm constructed to grip a suitable portion of the other member of the clutch, and operating means constructed to hold said arm in a position such that the shoes carried thereby do not grip said second member, substantially as described.

4. The combination in a clutch, of two members, a rib on one of said members, an arm

pivoted to the other member at a point farther from the center of revolution of the clutch than said rib, shoes pivotally supported on said arm for gripping the rib, with means for holding the arm in a definite position when it is desired to turn one member of the clutch independently of the other, substantially as described.

5. The combination in a clutch, of a driving and a driven member, an arm fixed to one member having a piece movable bodily toward and from the center of revolution of the clutch, an arm pivoted to said movable piece at a point relatively distant from the center of revolution of the clutch, shoes pivoted to said arm and placed to engage a suitable gripping-surface on the second member of the clutch, with means for swinging said arm on its pivot and thereby causing said shoes to release said second member, substantially as described.

6. In a clutch, the combination of a driving and a driven member, an arm pivotally carried by one member, having a pair of gripping-shoes pivoted to it, the second member having a portion extending between said shoes for engagement thereby, the pivot of the arm being at a greater distance from the center of revolution of the clutch than the portion of the second member to be gripped, with a device whereby said pivoted arm may be held in a definite position with the shoes out of engagement with the gripping-surface of the second member, substantially as described.

7. In a clutch the combination of a driving and a driven member, an arm fixed to one of the members and carrying a piece free to move toward and from the center of revolution of the clutch, an arm pivoted to said movable piece having means for engaging a suitable portion of the second member of the clutch, means for moving said arm on its pivot to disconnect the two members of the clutch, and means for engaging the arm and independent of the moving means, for limiting the amount of movement of the said arm, substantially as described.

8. The combination in a clutch, of a hollow shaft, an arm fixed thereto, a second arm pivotally supported upon the first arm having means constructed to engage the second member of the clutch, and a device in the hollow shaft having means for positively moving said arm so as to release the clutch members and hold the engaging means out of action, substantially as described.

9. The combination in a clutch, of a driving and a driven member, an arm fixed to one member, a slide movable thereon in a radial line of said clutch, a U-shaped arm pivoted to said slide, shoes pivoted to the sides of said U-shaped arm, a portion of the second member of the clutch extending between said two shoes, a radially-moving piece for engaging said pivoted arm and thereby holding said shoe out of engagement with the projecting

member of the clutch, and means carried by the shaft for operating said piece, substantially as described.

10. In a clutch, the combination of a shaft, 5 a casing carried thereby having an inwardly-projecting flange, an arm keyed to the shaft, a slide movable on said arm, a second arm having a pivotal connection to said slide at a point relatively distant from the center of revolution of the clutch, a pair of shoes carried by said arm and constructed to engage opposite faces of the flange on the other member of the clutch, a piece movable through an opening in the shaft for holding the pivoted 15 arm in a definite position and a longitudinally-movable piece in the shaft for actuating said piece to cause the shoes to disengage the flange, substantially as described.
11. In a clutch, the combination of a driving 20 and a driven member, an arm carried on one member having means for gripping a suitable portion of the other member, the point of support of said arm being farther from the center of revolution of the clutch than said 25 portion designed for the gripping means, and a device for actuating said gripping means, said device including a longitudinally-movable shaft having a cam-surface with means

operatively connecting the gripping means with said surface and operated by movement thereof for positively moving said gripping means to release the clutch members, substantially as described.

12. The combination in a clutch having driving and driven members, of a shaft, an arm having a shoe or shoes and pivoted to one of said members, a portion on the other member for engagement with the shoes, said portion being placed nearer the center of revolution of said clutch than the pivot of said arm, a movable piece having a cam-surface and a device operatively connecting the pivoted arm with the said movable piece, said device being arranged so that its movement under the action of said cam-surface will 40 positively move the arm to cause its shoe or shoes to disengage the second member of the clutch, substantially as described.

In testimony whereof I have signed my name to this specification in the presence of 50 two subscribing witnesses.

PERCY E. VARNEY.
